UNITED STATES PATENT OFFICE.

FRANK B. VORACEK, OF PORTLAND, OREGON.

AIRPLANE.

Original application filed October 18, 1920; Serial No. 417,535. Divided and this application filed April 18, 1922. Serial No. 555,393.

To all whom it may concern:

Be it known that I, FRANK B. VORACEK, a citizen of the United States, residing at Portland, in the county of Multnomah and 5 State of Oregon, have invented new and useful Improvements in Airplanes (Case B), of which the following is a specification.

This invention relates to improvements in airplanes and is a division of an application 10 filed by me Oct. 18, 1920, Serial No. 417,535.

An object of the present improvement is the provision of a novel arrangement of both vertical and horizontal rudders, together with means for controlling the operation 15 of the rudders, whereby the aviator will at all times have perfect control of his machine.

With the above and other objects in view, the invention further includes the following 20 novel features and details of construction, to be hereinafter more fully described, illustrated in the accompanying drawings and pointed out in the appended claims.

In the drawings:—

25 Figure 1 is a plan view of an airplane showing the application of the rudders and the controlling means therefor.

Figure 2 is a side elevation of the same partly broken away,

30 Figure 3 is a section on the line 3—3 of Figure 1.

Figure 4 is a horizontal section on the line 4—4 of Figure 3.

Figure 5 is a section on the line 5—5 of 35 Figure 1.

Figure 6 is a fragmentary plan view illustrating a different arrangement of elevating rudder.

Referring in detail to the drawings, where- 40 in like characters of reference denote corresponding parts, the invention is shown as applied to a machine of the triplane type and includes a lower plane 11, an upper plane 12 and an intermediate plane 13. 45 These planes may be of any desired structure, the ones shown being provided with tapered ends 14.

The fuselage of the machine is indicated at 15 and extends transversely through the 50 wings and may carry at its rear end spaced rigid stabilizing planes 16, whose structure may be of any suitable character. The planes 16 may be connected by struts 17 of suitable material and size.

55 The invention contemplates means for

controlling the machine and for this purpose there is mounted between the planes 16, vertical rudders 18, the latter being pivotally supported as indicated at 19 upon suitable shafts. Any number of these rudders 18 may 60 be placed upon opposite sides of the center of the machine. Each of the shafts 19 has secured thereon a grooved pulley 20 and passing around this grooved pulley is a cable 21, which also passes around the centrally arranged shaft 22. The cable is then carried forward as indicated at 23 and is secured to a suitable control mechanism, which includes a steering wheel 24. By operating this wheel, the rudders 18 may be moved 65 upon their pivots to control the horizontal movement of the machine.

Also pivotally mounted between the planes 16 is a horizontal rudder 25, whose shaft 26 has secured thereon a grooved pulley 27. Passing over this pulley is a cable 28, which leads to a suitable controlling mechanism, including a steering wheel 29. The wheels 24 and 29 may be arranged one 70 above the other as shown in the drawings, or any other suitable arrangement may be employed.

In Figure 6 there is illustrated a different arrangement of horizontal rudders. These rudders are positioned at the forward edges 75 of the stabilizing planes 16 and are indicated by the reference numeral 30. They are pivotally mounted as shown at 31 and are controlled by a cable 32, which passes over a grooved pulley 33 and leads to a suitable control. The rudders 30 are arranged one above the other and are connected by links 34, so that a movement of the lower rudder through the operation of the cable 32, will impart a like movement to the other 80 rudder.

The invention is susceptible of various changes in its form, proportions and minor details of construction and the right is herein reserved to make such changes as properly fall within the scope of the appended 85 claims.

Having described the invention what is claimed is:—

1. In an airplane, the combination of a 90 fuselage tapering toward both ends and terminating in a blunt nose, and having a double deck tail plane extending horizontally from both sides of the fuselage, with a plurality of vertical shafts disposed in spaced 95 100 105 110 115 116

relation along the longitudinal center line terminating in a blunt nose, and having a double deck tail plane extending horizontally from both sides of the fuselage, with a horizontal shaft rotatably mounted at the longitudinal center line of the tail plane and extending a substantial distance toward both sides of the fuselage, a driving pulley at the center of the shaft, a vertical steering post in the blunt nose of the fuselage, a tube revolvably mounted on the steering post, a steering wheel attached to the upper end of the steering post, a steering pulley attached to the lower end of the steering post, an endless cable between the driving pulley and the steering pulley, and vertical rudders mounted on the vertical shafts.

2. In an airplane, the combination of a fuselage tapering toward both ends and

In testimony whereof I affix my signature.

FRANK B. VORACEK.
